INVENTOR

BY Lancaster Z. Jenkins,
John A. Dederer, Esq.,
ATTORNEY.

UNITED STATES PATENT OFFICE.

LANCASTER Z. JENKINS, OF PHILADELPHIA, PENNSYLVANIA.

PAINT OR OTHER BRUSH.

SPECIFICATION forming part of Letters Patent No. 431,264, dated July 1, 1890.

Application filed January 31, 1890. Serial No. 338,790. (Model.)

To all whom it may concern:

Be it known that I, LANCASTER Z. JENKINS, a citizen of the United States, residing in the city and county of Philadelphia, State of Pennsylvania, have invented a new and useful Improvement in Paint or other Brushes, which improvement is fully set forth in the following specification and accompanying drawings.

10 My invention consists of novel means for connecting the bridle of a paint or other brush to the same, as will be hereinafter set forth, and pointed out in the claims.

Figures 1 and 2 represent perspective views 15 of a brush embodying my invention. Fig. 3 represents a section of a portion of a brush, the bridle being omitted therefrom. Fig. 4 represents a partial view of a brush, showing the cord which forms the bridle as fastened 20 to one of the hooks before winding the same and the other end as fastened to the hook after the same has been wound.

Similar letters of reference indicate corresponding parts in the several figures.

25 Referring to the drawings, A designates a paint-brush of ordinary construction, and B designates the bridle thereof.

C designates hooks on the head of the brush, the shanks D of the same being interposed 30 between the cap or wrapping E of the brush and the bristles and appearing on the outside of the cap or wrapping between the same and the inner portion of the bridle. The cord or twine of which the bridle is formed is secured to one of the hooks, leaving an end 35 piece F of sufficient length to reach to the bottom of the bridle and return to the starting-hook. The cord is then passed around the brush from the starting-hook to the lower 40 edge of the bridle, then looped around the same, and connected with the other hook. The free end of the cord below the bridle is then secured to the starting-hook.

In practice the hooks are formed of wire 45 or other pliable material, so that the ends of the bridle may be bent around or hitched to said hooks. A blow is then imparted to the hooks, so that they are closed upon the ends of the cords, and thus said ends remain firmly

connected with the hooks. It is evident that 50 the hooks may be afterward opened out and the ends of the cord released therefrom, whereby the bridle may be removed, if so required.

Eyes may be substituted for the hooks, as 55 shown in dotted lines at the left of Fig. 1, and the ends of the cord tied thereto; but this is not as desirable as the hooks.

It is evident that pieces of wire may be interposed between the cap or wrapping of the 60 bristles and their outer or projecting ends bent up to form hooks without, however, producing different results.

By forming a bridle of cord wound around the brush a flexible bridle is provided which 65 yields readily during the use of the brush.

Having thus described my invention, what I claim as new, and desire to secure by Letters Patent, is—

1. A brush having a bridle connected therewith by means of hooks attached to the head 70 of the brush, the ends of the cord comprising the bridle being hitched or otherwise secured to said hooks, substantially as described.

2. A brush having a cap, a bridle consisting of cords, and hooks having their shanks between the cap and the bristles of the brush and their hook portions between the cap and the bridle, the cord of the bridle being fastened at or near both of its ends to the said 80 hooks, said parts being combined substantially as described.

3. A brush having a cap, a bridle, and hooks, the latter having their shanks between the cap and the bristles of the brush and their 85 hook portions between the cap and the upper edge of the bridle, and the cord of the bridle having an end piece F, adapted to embrace the bridle, said parts being combined substantially as described.

4. A brush having a flexible bridle consisting of cord secured at both ends to hooks at the upper end of the bridle, substantially as described.

LANCASTER Z. JENKINS.
